UNITED STATES PATENT OFFICE.

WILBER H. VAN SICKEL, OF LANGHORNE, PENNSYLVANIA, ASSIGNOR TO THOS. H. DALLETT CO., A CORPORATION OF NEW JERSEY.

STONE-DRESSING MACHINE.

1,227,095.

Specification of Letters Patent.

Patented May 22, 1917.

Application filed June 10, 1916. Serial No. 102,829.

To all whom it may concern:

Be it known that I, WILBER H. VAN SICKEL, a citizen of the United States, residing at Langhorne, county of Bucks, and 5 State of Pennsylvania, have invented a new and useful Improvement in Stone-Dressing Machines, of which the following is a full, clear, and exact description, reference being had to the accompanying drawings, which 10 form a part of this specification.

My invention relates to stone-surfacing or dressing machines of the portable variety. The particular objects of my invention are to provide a machine the base of which, 15 while being readily movable, shall yet prove sufficiently substantial to carry a pivoted tool arm of considerable reach without either guying or supports in a satisfactory manner; which tool arm shall also be such 20 that the surfacing tool carried thereby has a maximum range of movement, from the ground up and from one side to the other, with the base of the machine remaining in one set position.

25 Further objects of my invention are improvements in the manner of setting the machine, provision for leveling when placed upon uneven ground, and a construction of the tool holding arm which allows of readily 30 and easily mounting the surfacing tool in place or removing it.

Other advantages of my invention will be brought out in the description of the machine.

35 My invention will be readily understood from the following description of a preferred embodiment thereof together with the accompanying drawings, in which:

Figure 1 is a side view of the machine.

40 Figs. 2 and 3 are rear views in different positions.

Fig. 4 is a plan view taken in section on line 4—4 of Fig. 1.

Fig. 5 is a partial section on line 5—5 of 45 Fig. 2.

Fig. 6 is a detail view in section on line 6 of Fig. 2.

Fig. 7 is an end view of the tool carrying arm shown in Fig. 6.

50 In general, the base *a* of the machine is supported above the ground on adjusting screws *b* at the four corners. This base carries the pedestal or carriage *c* and is provided with ways *d* wherein the pedestal is 55 movable to and from the work.

The pedestal has a pivoted head *e* which carries the shaft *f* to one end of which is attached the arm *g* for carrying the tool supporting frame. This frame comprises a portion *h* pivoted to the end of arm *g* at *i*, and 60 a portion *j*, connected to portion *h* by bolts and springs *k* as shown in Fig. 1. This is for the purpose of allowing a certain movement of the portion *j* with respect to *h*, which provides enough resilience in the action of the tool to prevent jars and shocks and produce the best surfacing results. 65

Portion *j* has a head *l* which forms a seat for the pneumatic hammer or tool *m*, which is of the usual variety of air-operated automatic piston type. Portion *h* is provided with an extension on the opposite side of pivot *i* for a counter weight *n*, which may be adjusted to just balance the weight of the tool and its supporting frame. Thus 70 the tool may be readily and easily turned about pivot *i*, and no more effort is required to raise than to lower it, no matter what position the tool carrying frame may assume. 75

Opposite to the frame carrying arm *g*, on shaft *f*, is attached an arm with an adjustable counter weight *o* by which arm *g* and all that it carries may be counterbalanced. Thus, however shaft *f* may be turned, the 80 tool carrying frame is readily counterbalanced and may be raised and lowered with equal ease. 85

By means of the two pivots *i* and *f* and the counterweights *n* and *o*, the tool *m* may 90 be moved in a vertical plane to apply its surfacing action anywhere within the limit of a radius equaling the combined lengths of the arm *g* and the tool carrying frame. This may all be done with a single setting 95 of the heavy base *a* of the machine.

If the surface *z* to be dressed is not exactly normal to shaft *f*, said shaft may be turned to normal position. As shown, the depending pintle *e'* of this head passes through 100 a vertical bearing *p* in pedestal *c*. This bearing is split at one side, forming a spring clamp which by means of hand screw *q* may be made to clamp head *e* in any position desired. The tool may be advanced against the surface *z* by sliding the pedestal in the ways *d* on the base of the machine. For this purpose the pedestal has depending ears *r* and the base carries an interior bracket *s*, 105 through which passes a screw-threaded rod 110

t. This rod engages a nut *u* held from turning in the depending ears *r*, and the rod is turned by hand wheels *v* actuating the worm gearing *w*.

5 The adjusting screws *b* are provided with pivoted feet *b'* for resting upon the ground. The screws engage square nuts *x* which rest in appropriate square seats within the base near the corners thereof, and may be inserted and withdrawn through openings *y* in the sides of the base. It will be noticed that openings *y* are at a slightly lower level than the seats for the square nuts, so that while there is any weight upon the screw the nut cannot by any possibility be forced sideways from its seat. Each of these adjusting screws is turnable by a rod being inserted in holes provided in the head of the screw, which may thus be screwed down until it takes its share of the weight of the machine, or until the corner which it supports is raised to the level desired.

In assembling a tool of the class described ready for work, the tool is regularly built up upon the tool carrying head *l* of the carrying frame. As the tool parts are in themselves heavy and cumbersome, this is a difficult task if the tool is assembled in the horizontal position in which it is to be used.

30 To overcome this difficulty, I have made head *l* turnable in the end of portion *j*, in Figs. 6 and 7. The head has a neck 10 which enters and turns in the end of *j*. Projecting from the flange of the head is a bracket 11 having a hole into which the base of tool *m* fits and is secured in the usual manner.

The flange of head *l* is attached to portion *j* by bolts, one of which, 12, is slideable in a concentric slot 13 provided in the flange and extending a distance of at least 90°. By taking out all the bolts except bolt 12, and by loosening the nut of bolt 12, the head *l* may be turned in the portion *j* so that the tool carried by bracket 11 extends vertically. This may be done after the frame-carrying arm is brought and held in a horizontal position. To hold the frame in this position during the mounting 50 or demounting of a tool, I provide a rod 14, horizontally slideable in a lug 15 on one side of pedestal *c*. In the extension carrying the counterweight *n*, I provide a hole 16 in such position that when the tool-carrying frame 55 has been brought down to a convenient height to work upon and turned to a horizontal position hole 16 will align with rod 14. The rod is then slid along through hole 16, lug 15 being long enough to maintain rod 60 14 horizontal even with weight imposed on the end of it. Cotter pins are provided near the ends of rod 14 to be removed when necessary.

Having brought the tool-carrying frame 65 down into horizontal position as described,

the tool is mounted thereon as follows: Head *l* is turned as described until bracket 11 is horizontal, and nut of bolt 12 is tightened to hold the head in this position. Then the tool *m* is built up thereon, which may be as readily done as if it were on a work bench or table. Bolt 12 is then loosened and the tool is turned down to horizontal working position and bolt 12 tightened again and other bolts inserted to hold head *l* rigidly in place.

Now counterweight *n* is adjusted on its arm to counterbalance the frame and tool. Also counterweight *o* is likewise adjusted to balance parts carried by arm *g*. Then rod 80 14 is retracted out of hole 16 to the position shown in Fig. 1, and the perfectly balanced tool is ready for operation.

When necessary to remove the whole machine, a fixed bail 17 provides handling means whereby a crane or other hoist may be readily attached.

Having now fully described my invention, what I claim and desire to protect by Letters Patent is:—

1. The combination with a horizontally movable pedestal, of an arm and a counter-balancing weight pivotally mounted on the pedestal on a horizontal axis, a tool-carrying frame and a counter-balancing weight pivotally mounted on the arm on an axis parallel to the first axis, and a head on the frame arranged to support a pneumatic tool in a position to cause its reciprocable member to operate parallel to said axes.

2. In a surfacing machine, the combination with a pedestal, of a head turnable on a vertical axis on the pedestal, an arm and a counter-balancing weight mounted on a horizontal axis on the head, a tool-carrying frame and a counter-balancing weight mounted on a horizontal axis on the arm, and a surfacing tool support carried by the frame.

3. In a surfacing machine, the combination with a base, of a pedestal adjustable horizontally thereon, a head turnable on a vertical axis on the pedestal, a horizontal shaft turnable on the head, an arm and a counter-balancing weight carried by the shaft on opposite sides of the pedestal, a tool-carrying frame and a counter-balancing weight mounted on the arm on an axis parallel to said shaft, and a surfacing tool support carried by the frame whereby the tool 115 may be held in angular relation to the frame.

4. In a machine for dressing vertically extending surfaces, the combination with a base, of a pedestal supported on the base and movable horizontally thereon to regulate the distance between the pedestal and the surface to be dressed, a head turnable in a vertical axis on the pedestal to bring the parts carried by the head in proper angular relation to the surface to be dressed, an arm 125

pivotedly supported on the head on a horizontal axis, a counter-balanced tool-carrying frame pivotally supported on the arm on an axis parallel to the axis on which the arm is supported, a weight counter-balancing the arm and the counter-balanced tool-carrying frame carried thereby, and a surfacing tool support carried by said frame and positioned to support the tool to cause the latter to extend in a direction parallel to said horizontal axes, thus enabling the tool to oper-

ate on a vertical surface by movement in a vertical plane throughout a radius equaling the combined lengths of the said arm and frame and to be properly counter-balanced in any position within its range of movement. 15

In testimony of which invention, I have hereunto set my hand, at Philadelphia, on this 7th day of June, 1916.

WILBER H. VAN SICKEL.
